UNITED STATES PATENT OFFICE.

CECIL E. MARTIN, OF WABASH, INDIANA.

RIVETING MACHINE.

Application filed May 14, 1925. Serial No. 30,311.

To all whom it may concern:

Be it known that I, CECIL E. MARTIN, a citizen of the United States, residing at Wabash, in the county of Wabash and State of Indiana, have invented certain new and useful Improvements in a Riveting Machine; and I do hereby declare the following to be a full, clear, and exact description of the invention, such as will enable others skilled in the art to which it appertains to make and use the same.

This invention relates to improvements in riveting machines, particularly in an improved means for holding the rivets in place and swinging the rivet carrier aside after the rivet has come in contact with the work.

A further object of this invention is to provide a device for forcing the carrier into operative position for receiving rivets.

Other objects of this invention will appear from the following description and claims.

In the drawings,

Fig. 1 illustrates a vertical side elevation view of the riveting machine in assembled form with a section of the tubular supporting rod broken away showing the foot lever which is connected to the operating arm of the plunger.

Fig. 2 represents a vertical front elevation view of a portion of Fig. 1.

Fig. 3 illustrates a cross section of the rivet feeding tube taken at 3-3 of Fig. 1.

Fig. 4 represents a vertical side elevation view on enlarged scale of the feeding, carrying and releasing mechanism for the riveting machine, in raised position.

Fig. 5 illustrates a vertical side elevation view of Fig. 4 in lowered position.

Fig. 6 shows a vertical front elevation view of the plunger, carrying, and releasing mechanism in raised position, with the spacing washers holding the cotter pin in section.

Fig. 7 illustrates a cross sectional view of Fig. 6 taken at 7-7.

This invention is particularly adapted to be used in connection with any riveting machine of a suitable type, for instance, in a machine having a foot press 1, a return tension spring 2 attached thereto, and a rod 3 extending upward through a tubular support 4, to a cross arm 5 adapted to operate a plunger 6, having a tension spring return 7. The plunger 6 being guided in slidable relation in a head portion 8 of the main body section 9, having a table or work supporting

portion 10. Attached to the main body portion of the machine is a rivet feeding tube 11 of a suitable design, which supplies a steady stream of rivets 12 to the rivet carrier 13, having a receiving slot 14 therein. The carrier 13 is rotatably mounted in the plunger 6, through an enlarged opening 15, on a cotter pin 16, one end of the cotter pin 16 being adapted to receive one end of a tension spring 17, the other end of spring 17 being attached to a cotter pin extending through a limiting collar 19 and plunger shaft 6. The enlarged opening 15 will enable the tension spring 17 to bring the carrier 13 firmly against the rivet 12 at the bottom end of the plunger 6. The other end of the cotter pin 16 is adapted to receive in addition to the carrier, 13, suitable spacing washers 20 and 21 and a tension spring 22, the tension spring 22 having an arm 23 extending to a lock 24 integrally a part of a latch 25. The spring 22 will function and hold the dog or latch 25 in locked relation with the plunger 6 at the point 26, thereby, at the same time holding the carrier 13, with the rivet 12 at the lowered position clearly disclosed in Figure 6. The dog or latch 25, is pivotally connected at the point 27 to the carrier 13. An arm 28 integrally connected with the carrier 13, is adapted to receive at its end 29 one end of a tension spring 30. The other end of spring 30 being attached at a point 31 of an extension arm 32. The extension arm 32 extending downward a suitable distance in order to contact with the arm 28, thereby forcing carrier 13 into operative position for receiving a rivet 12, from the feed tube 11 when the plunger is in raised position. The extension arm 32 is further pivotally mounted at 33 to the head portion 8 of the main body section 9. A specially designed trip release 34 is pivotally mounted at 35 on carrier 13, one end of the release trip 34 being adapted to slidably contact at 36 with the work on the table portion 10; the other end of the trip release 34 being adapted to receive in loose relationship the lug 24 extending from the dog or latch 25.

Obviously, when the trip release 34 strikes the work 10 at 36, the latch 25 will be released from locked relationship and carrier 13 will swing upward from the power exerted by the tension spring 30, and the extension arm 32 coming in contact with arm 28 of the carrier will tend to force the carrier

into operative position for receiving another rivet from the feeding tube 11 as clearly disclosed in Figure 4.

In operation with an ordinary riveting machine of the type described herein, it is merely necessary to press downward on the foot lever 1 which will bring plunger 6 downward with a rivet hanging firmly in place in the carrier at the lower end of the plunger, the tension spring 17, acting to hold the rivet firmly in position. The carrier being released by a trip lever 34 pivoted on the carrier, as the release trip comes in contact with the work on the table of the machine, the carrier will be allowed to swing upwardly out of the way while the rivet continues on downward and is spread, making an efficient riveting operation.

What I claim is:

20 1. The combination with a riveting machine having a table portion, a plunger, and a head for the plunger, of a rivet carrier pivotally mounted on the plunger, and means for holding the rivet carrier in fixed relation to the plunger comprising a latch pivotally mounted on the carrier.

25 2. The combination with a riveting machine having a table portion, a plunger, and a head for the plunger, of a rivet carrier pivotally mounted on the plunger, means for holding the rivet carrier in fixed relation to the plunger comprising a latch pivotally mounted on the carrier, and means for releasing the latch.

30 3. The combination with a riveting machine having a table portion, a plunger, and a head for the plunger, of a rivet carrier pivotally mounted on the plunger, means for holding the rivet carrier in fixed relation to the plunger comprising a latch pivotally mounted on the carrier, and means for releasing the latch consisting of a trip release lever.

35 4. The combination with a riveting machine having a table portion, a plunger, and a head for the plunger, of a rivet carrier pivotally mounted on the plunger, means for holding the rivet carrier in fixed relation to the plunger comprising a latch

pivotally mounted on the carrier, and means 50 for releasing the latch consisting of a trip release lever pivotally mounted on the carrier, one end of the trip lever being connected to the latch and the other end adapted to contact with the table portion, to thereby release the latch from locked relationship with the plunger.

5. The combination with a riveting machine having a table portion, a plunger, and a head for the plunger, of a rivet carrier 60 pivotally mounted on the plunger, and means for raising the carrier on the pivot for adjusting its position.

6. The combination with a riveting machine having a table portion, a plunger, and a head for the plunger, of a rivet carrier pivotally mounted on the plunger, and means for raising the carrier on the pivot 65 for adjusting its position comprising a tension spring and a lever arm.

7. The combination with a riveting machine having a table portion, a plunger, and a head for the plunger, of a rivet carrier pivotally mounted on the plunger, and means for raising the carrier on the pivot 75 for adjusting its position comprising a tension spring and a lever arm, the tension spring being attached at one end to the lever and at the other end to an extension of the carrier, and the lever being designed to swing from the head and adapted to adjust the carrier into position.

8. The combination with a riveting machine having a table portion, a plunger having an enlarged opening therein, and a head 85 for the plunger, of a rivet carrier pivotally mounted on the plunger, the pivot for the carrier being received in the enlarged opening in the plunger, and means for tightening the rivet carrier against the rivets comprising a tension spring adapted to move the rivet carrier relative to the plunger, said movement being permitted by the enlarged opening through which the pivot for the rivet carrier is extended.

In testimony whereof I affix my signature.

CECIL E. MARTIN.
